Specification for Design.

Patented Aug. 2, 1921.

Application filed October 21, 1920. Serial No. 418,628. Term of patent 14 years.

To all whom it may concern:

Be it known that I, PHILIP C. WENTWORTH, a citizen of the United States, residing at Providence, in the county of Providence and State of Rhode Island, have invented a new, original, and ornamental Design for a Paper-Weight or like Article of Manufacture, of which the following is a specification, reference being had to the accompanying drawing, forming part thereof.

Figure I is a side view of a paper weight or like article of manufacture showing my new design.

Fig. II is a plan thereof, and

Fig. III is an end view.

I claim:

The ornamental design for a paper weight or like article of manufacture as shown.

PHILIP C. WENTWORTH.
